UNITED STATES PATENT OFFICE.

GEORGE H. DAY, OF ROCHESTER, NEW YORK, ASSIGNOR TO BAUSCH & LOMB OPTICAL COMPANY, OF ROCHESTER, NEW YORK, A CORPORATION OF NEW YORK.

DESIGN FOR A SPECTACLE CASE.

Application filed March 27, 1926. Serial No. 17,088. Term of patent 14 years.

To all whom it may concern:

Be it known that I, GEORGE H. DAY, a citizen of the United States, and a resident of Rochester, county of Monroe, and State of New York, have invented a new, original, and ornamental Design for a Spectacle Case, of which the following is a specification, reference being had to the accompanying drawings.

In the drawings,

Fig. 1 is a plan of a spectacle case embodying my new design, shown closed; Fig. 2 is an elevation of the same, and Fig. 3 is a perspective, showing the case open.

I claim: The ornamental design for a spectacle case substantially as shown.

GEORGE H. DAY.
